UNITED STATES PATENT OFFICE.

RICHARD N. B. PETERSEN, OF VINTON, IOWA.

INK-FOUNTAIN FOR RULING-MACHINES.

SPECIFICATION forming part of Letters Patent No. 519,025, dated May 1, 1894.

Application filed September 22, 1893. Serial No. 486,202. (No model.)

To all whom it may concern:

Be it known that I, RICHARD N. B. PETERSEN, a subject of the King of Denmark, residing at Vinton, in the county of Benton and State of Iowa, have invented certain new and useful Improvements in Ink-Fountains for Ruling-Machines; and I do hereby declare the following to be a full, clear, and exact description of the invention, such as will enable others skilled in the art to which it appertains to make and use the same.

The object of this invention is to obviate much of the labor and inconvenience incident to the operation of a ruling machine, by providing it with means for automatically supplying ink to the pens.

The invention consists essentially in providing one or more fountains for the pens, so constructed as to supply them with the requisite amount of ink from minute openings in the bottom, the holes being so small as to retain the ink except when brought into contact with the surface of the pens, or the like.

It further consists in means for regulating the flow of ink, and other details of construction, which will be hereinafter fully set forth and claimed.

In the accompanying drawings, forming a part of this specification, Figure 1 is a perspective view of a device embodying my invention. Fig. 2 is a central, longitudinal section of the fountain. Fig. 3 is a transverse section of the same, in the line *a b*.

Similar letters of reference indicate corresponding parts.

The common method of supplying ink to the pens of a ruling-machine is to saturate, by means of a brush dipped in ink, a strip of flannel or felt placed on the pen-clamp and overlapping the upper part of the pens. This is an operation requiring careful attention, since the supply is soon exhausted. It has its disagreeable features, also, as the operator in "setting up" his machine for work is obliged to handle these ink-saturated strips more or less, so that his hands are deeply stained with ink. To obviate these objections to the common method of ruling I have devised the apparatus hereinafter described.

Referring now to the drawings, A is the

pen-clamp of an ordinary ruling-machine, provided with the supplemental clamp B for extension pens. C is the gripper used in connection with extension pens, and E is a short card of pens. All of these parts are of common and well known construction, and need not be described.

F is an ink-fountain adapted to be mounted so as to rest on the inclined plate forming the head of the pens, and discharge thereon a limited quantity of ink. This fountain is composed of two parts, an outer vessel F, triangular in cross-section, and an inner one F' quite similar to it in form, but truncated at the bottom. In practice I form a little curve *f* near the lower angle of the outer vessel, thus enlarging this part of it a little. In this angle I place a small strip of felt *f'*, to prevent excessive or erratic flow of ink, and render it steady and uniform. The angle of *f* the trough is perforated by a series of minute holes *a a a*, so small that the ink does not escape from them until the angle is brought into contact with a damp or attractive surface. The ink-holding vessel or trough F' is also 75 perforated at the bottom with holes *e e*, which may be, and preferably are, considerably larger than those in the outer one. To regulate the flow of ink through these holes I provide the fountain with a valve G. This consists of a small bar of metal *g* surrounded, or at least faced on the upper side, by rubber packing *g'*. In flanges *f'' f''* are mounted two screws H H, having grooves *h h* near the lower end engaging with suitable forks *c c* in 85 the ends of the bar *g*. By turning these thumb-screws a very nice and accurate adjustment of the valve is obtained, and the flow of ink is thereby adjusted or stopped at will. From one side of the fountain extends 90 a flange F'' for connection with the gripper C. This flange may be a part of the inner receptacle, as in Fig. 1, in which case the inner and outer vessels are permanently connected together, as by soldering; or it may 95 extend from the outer vessel, as in Fig. 3. In this case the parts need not necessarily be connected. The fountain should be made of some metal not readily corrosive, such as brass or German silver.

It is to be understood that a considerable number of these fountains will be required to supply different groups of pens, and with different colors of ink. The length of the 5 fountains may be made such as convenience suggests, though extreme length is not necessary, as a row of shorter fountains may supply a wide pen-space as well as a single long fountain.

10 The device, as will be seen, is simple in construction, and only requires suitable adjustment and attention to cleanliness to be entirely automatic. Much of the attention of the operator may thus be dispensed with, 15 and he be at liberty to attend to other matters or to another machine. The necessity for staining the fingers is also entirely removed, as in the mounting of the pens and fountains, and the operation of the ruling 20 machine the hands need not be brought into contact with the ink at all.

Having thus described my invention, I claim—

1. An ink-fountain for ruling machines 25 having an inner vessel to hold the ink, perforated at the bottom, and provided with suitable means for regulating the flow of ink through the perforations, and an outer vessel 30 with minute perforations in the bottom, adapted to retain the ink when detached from the pens, but permitting the flow thereof

when in contact with said pens, substantially as described.

2. In an ink-fountain for ruling machines, the combination of an inner, ink-holding vessel, perforated at the bottom, an adjustable valve adapted to open or close said perforations, an outer vessel with minute perforations in the bottom, and a strip of felt over said perforations, substantially as and for 40 the purpose set forth.

3. In an ink-fountain for ruling machines, the combination of the vessel F having minute perforations at the bottom, and provided with the felt strip f', the inner vessel F' perforated at the bottom, the valve G and adjusting screws H H, substantially as and for 45 the purpose set forth.

4. In an ink-fountain for ruling machines, the combination of the vessel F having minute perforations at the bottom, and provided with the felt strip f', the ink-holding vessel F' perforated at the bottom, the valve G, adjusting screws H H, and flange F'', substantially as and for the purpose set forth. 50

In testimony whereof I affix my signature in presence of two witnesses.

RICHARD N. B. PETERSEN.
